CURTAIN ROD MOUNTING

Richard C. Vogt, West New York, N. J.

Application June 23, 1933, Serial No. 677,178

8 Claims. (Cl. 156—22)

This invention relates more particularly to mountings for supporting a number of curtain rods, drapery rods etc. on a window frame. An important object of the invention is to provide such a mounting of generally improved design.

Other objects of the invention will appear hereinafter.

In the drawing, Fig. 1 is a front view showing a plurality of curtain rods supported upon a window frame by the improved mounting;

Fig. 2 a top plan view of the structure shown in Fig. 1;

Fig. 3 a view similar to Fig. 1 showing drapery rods mounted at the window frame along with curtain rods;

Fig. 4 a perspective view of one of the rod supporting brackets on a larger scale;

Fig. 5 a section on the line 5—5 of Fig. 4;

Fig. 6 an enlarged section on the line 6—6 of Fig. 3;

Fig. 7 a perspective view of an end portion of one of the curtain rods;

Fig. 8 a detail perspective view showing the hinge mounting of a drapery rod on one of the bracket slides; and

Fig. 9 is a perspective view of a bracket slide provided with a curtain rod support and bearing an ornament.

The improved mounting includes a pair of brackets designed for ready attachment to and detachment from the upper corners of a window frame and provided with improved supports for curtain rods and drapery rods and ornaments. Each bracket has a clamping and anchoring structure operable diagonally of a window frame corner to securely but detachably hold the bracket to the frame without the employment of screws or nails.

Each bracket includes a substantially flat body 1 formed of a single piece of sheet metal. The body has a horizontal upper edge and a vertical side edge. Along said edges the body has rearwardly turned integral flanges which bear inwardly turned anchoring barbs 2 to engage the outer corner edges of the window frame. There are several of these barbs at each of said edges and spaced a material distance therealong. In the present instance the side edge of the bracket body is materially longer than the upper edge.

The body is integrally formed with a shank 3 extending downwardly and inwardly away from said edges, diagonally of the said upper corner. This shank is flat and flush with the body of the bracket and has straight parallel side edges.

Mounted on the shank 3 is a slide 4. The

latter is also formed of a single piece of sheet metal with opposite edges folded around the straight edges of the shank to form retaining guides 5. Along a longitudinal central line the slide is pressed outwardly to form a semi-tubular spring housing 6. A tension spring 7 is disposed in said housing and has its outer end anchored to the slide and its inner end anchored to the bracket body. The spring tends to pull the slide inwardly along the shank. To adjust the tension of the spring and the position of the slide along the shank the anchorage of the inner end is formed by a screw 8 and the shank has a longitudinal row of screw holes 9 to selectively receive said screw. At the outer end of the slide the under plies of the folded margins have integral anchoring barbs 10. The latter are bent under and twisted to proper positions for effective anchoring engagement with the window frame within the adjacent inner corner thereof.

For the support of curtain rods the bracket body has a number of slotted ears. In the present instance there are three ears. Two of them are formed by a substantially U-shaped strip 11 of sheet metal. The bend of said strip is permanently secured to the front face of the bracket body by riveting or otherwise, at a point spaced materially inward from the vertical edge of the bracket body. The legs of the strip project forward and form the ears 12 and 13. The ear 12 projects materially farther than the ear 13. At its vertical edge the bracket body has an integral ear 14 bent forward and then laterally. The means for supporting the curtain rods on the ears will be described hereinafter.

There are provided means for hingedly mounting drapery rods also upon the brackets. Between the ears 12 and 14 and I-shaped slit is cut in the bracket body and the margins along the vertical reach of said slit are pressed forward to form parallel vertical guides 15. A slide 16 is fitable downward into said guides to detachably hold it to the bracket. Below the guides the bracket body is slit and pressed forward to form a stop 17 to limit the insertion of the slide. The slide is formed of a single piece of sheet metal. It is folded to form a tubular vertical socket 18, a vertical double-ply web 19 of material with and longitudinal base flanges 20 extending laterally in opposite directions and in a vertical plane at a right angle to the web. The base flanges are slidably fitable within the guides 15. When the slide is mounted on the bracket the socket forms a support for a drapery rod or for an ornament, as will be explained hereinafter.

In the employment of the brackets they are mounted upon the opposite upper corners of a window frame F. The barbs 2 of each bracket are engaged with the outer edges of the frame, at 5 opposite sides of the corner, and the slide 4 is pulled outward along the shank 3, against the resistance of spring 7, to bring the barbs 10 of the slide into anchoring engagement with the frame at opposite sides of the adjacent inner corner. The tension of the spring, exerted diagonally of said inner and outer corners, holds the barbs in tight anchoring engagement with the frame, and the bracket is thereby held securely in place. At the same time it is readily detachable from the frame by pulling the slide 4 downwardly along the shank 3, against the resistance of the spring 7, so that the anchoring barbs may be disengaged from the frame. The straight line arrangements of the upper barbs 2 10 and their engagement with the straight upper edge of the frame ensures accurate leveling of the rod-supporting ears at the opposite sides of the frame.

The supporting connections between the curtain rods, designated 21, 22 and 23, and the supporting ears on the brackets are of the general character disclosed in my U. S. Patent No. 1,857,991, dated May 10, 1932. The present structure of said connections is improved to 25 facilitate the attachment of the rods to the ears. The rods are extensible and in the present instance they are formed of a plurality of sections each formed of a sheet metal strip with its longitudinal edges folded rearward to form hook-like 30 flanges. The sections of each rod are telescoped, with the said flanges of one section slidably fitted within those of the other section. At each end the rod has a pair of longitudinally projecting 35 transversely spaced prongs 24. The latter are flexible and resilient and they are preferably formed by a strand of wire bent into U form. Adjacent its bend the U-shaped strand is secured to the rod by pressing inward portions of said longitudinal flanges of the rod around the strand. 40 The ends of the strand project to form the prongs and at their extremities they are curled to form 45 heads 25.

To receive the spring prongs 24 each of the bracket ears 12, 13 and 14 has a vertical slot 26 50 with closed ends. A tapering mouth leads from the forward edge of the ear to the medial portion of the slot. The mouth is defined by inwardly converging cam edges 27. The maximum outer width of the mouth exceeds the normal expanded 55 width of the prongs, and the minimum inner width of the mouth is materially less than that of the expanded prongs. The prongs are inserted by merely forcing them transversely through the mouth, the cam edges compressing the prongs. When passed through the mouth 60 the prongs expand to engage the closed ends of the slot. Thereby the rod is supported on the bracket. The heads of the prongs form stops to lock the prongs against endwise withdrawal. 65 The rods are readily released from the brackets by merely grasping the heads of the prongs and squeezing the prongs together to pass outward through the mouth.

The curtain rods 21 and 22 are entirely straight 70 while the outermost rod 23 has its ends bent rearward to bring the supporting prongs 24 into connecting relation to the outer bracket ears 14. As indicated at 28, the innermost rod 21 may have locking means to maintain a required length adjustment of the rod. Then when the brackets are

released from the window frame the locked rod 21 will hold the brackets in a fixed spaced relation and the brackets and rods will be held assembled in a unit for convenient handling.

In Figs. 1 and 2 the three curtain rods are shown 80 supported by the brackets, while the slides 16 are removed from the brackets. When drapes are to be suspended at the window frame the outermost curtain rod is removed and the slides 16 are applied to the brackets. To support the drapes 85 there are rods or poles 29 each having a rigid depending shank 30 at one end. Said shank is inserted downwardly into the slide socket 18. The shank is formed to fit rotatably in the socket and form a hinge connection. Thereby the drape 90 rods are supported to swing laterally on the window frame.

The slides 16 may also be employed to support 95 ornaments on the window frame. As shown in Fig. 9 there may be provided for each slide, an ornament 31 having a supporting shank 32 fittable into the socket of the slide. An ornament of the proper shape and size will serve to conceal the bracket structure above the curtains and drapes. The slides may also bear curtain rod supporting 100 ears. Fig. 9 shows a slide having an ear 33 fixed to its web 19 to project laterally. When the slides are so equipped with these ears the outermost ears 14 on the brackets may be omitted.

It will be seen that I have provided a curtain 105 supporting structure which is readily set-up and taken down and is capable of many adjustments and adaptations.

What I claim is:

1. A curtain rod mounting including a bracket 110 releasably attachable to an upper corner portion of a window frame and comprising a body formed of single piece of sheet metal and having a plurality of integral anchoring barbs spaced apart materially along a horizontal line and a plurality 115 of integral anchoring barbs spaced apart materially along a vertical line for anchoring respectively to the upper edge of the window frame and to an outer side edge thereof at opposite sides of an upper corner of the frame, a slide shiftably 120 borne by said bracket body, inner anchoring means borne by said slide, a tension spring connection between the bracket body and said slide to exert a tension upon said inner anchoring means and said barbs to anchor the bracket to 125 the window frame, and a curtain rod support borne by the bracket, said inner anchoring means and said materially spaced barbs along the vertical and horizontal lines being cooperable to accurately true the bracket and curtain rod support 130 on the window frame.

2. A curtain rod mounting including a bracket 135 releasably attachable to an upper corner portion of a window frame and comprising a body formed of a single piece of sheet metal and having a plurality of integral anchoring barbs spaced apart materially along a horizontal line and a plurality 140 of integral anchoring barbs spaced apart materially along a vertical line for anchoring respectively to the upper edge of the window frame and to an outer side edge thereof at opposite sides of an upper corner of the frame, the bracket body having a straight, flat integral shank to extend 145 diagonally of the window corner, a slide shiftably mounted on said shank and formed of a single piece of sheet metal with opposite side edges turned inward to form guides engaging the longitudinal edges of said shank and a longitudinal central portion bent outward to form a semi-tubular spring housing said slide having integral 150

- anchoring barbs to engage the window frame within the adjacent inner corner thereof and arranged in divergent relation to each other to dispose their points in direct opposition to the inner edges of the frame, a tension spring within said spring housing and anchored to the slide and to the bracket body and tending to pull the slide inward along the shank to hold the bracket anchored to the frame, and a curtain rod support borne by the bracket body said anchoring barbs on the slide and said anchoring barbs on the bracket body materially spaced along the horizontal and vertical lines being cooperable to accurately true the bracket and curtain rod support on the frame. 5. As an article of manufacture, a unitary mounting for rods to support window hangings or the like, comprising a bracket body for releasable attachment to an upper corner of a window frame and having a plurality of outer anchoring barbs spaced materially apart along a horizontal line and a plurality of outer anchoring barbs spaced materially apart along a vertical line for anchoring respectively to the upper edge of the window frame and to an outer side edge thereof at opposite sides of an upper corner of the frame, a slide borne by said bracket body to shift obliquely and having inner anchoring barbs spaced apart transversely of the direction of shift of the slide and diverging to effectively anchor to the adjacent inner corner edges of the window frame, a tension spring connection between the bracket body and said slide to hold all of said anchoring means in engagement with the frame to hold the bracket in place, a support for one of said rods borne by the bracket body, a slide having a vertical socket to support another of said rods, and guides borne by the bracket body to removably hold said latter slide to the bracket. 4. As an article of manufacture, a unitary mounting for rods to support window hangings or the like comprising a bracket body for releasable attachment to an upper corner of a window frame and having a plurality of anchoring barbs spaced materially apart along a horizontal line and a plurality of barbs spaced materially apart along a vertical line for anchoring respectively to the upper edge of the window frame and to an outer side edge thereof at opposite sides of an upper corner of the frame, a support for one of said rods borne by the bracket body, and a vertical socket borne by the bracket body to support another of said rods. 5. As an article of manufacture, a unitary mounting for a rod to support a window hanging or the like, comprising a bracket body for releasable attachment to an upper corner of a window frame and having a plurality of anchoring barbs spaced materially apart along a horizontal line and a plurality of barbs spaced materially apart along a vertical line for anchoring respectively to the upper edge of the window frame and to an outer side edge thereof at opposite sides of an upper corner of the frame, and a support for said rod borne by the bracket body. 6. A mounting for a rod to support a window hanging or the like, comprising a bracket body for releasable attachment to an upper corner of a window frame and having a plurality of anchoring barbs spaced materially apart along a horizontal line and a plurality of barbs spaced materially apart along a vertical line for anchoring respectively to the upper edge of the window frame and to an outer side edge thereof at opposite sides of an upper corner of the frame, a support for said rod borne by the bracket body, and additional anchoring means in tensioning connection with the bracket body and engageable with the window frame to cooperate with said anchoring barbs to releasably hold the bracket body to the frame. 7. A supporting bracket for a curtain rod, including a forwardly projecting rod-supporting ear having a vertical slot closed at its ends and an inwardly tapering mouth leading from the forward edge of the ear to the medial portion of the slot and of a maximum outer width exceeding the length of the slot and a minimum inner width materially less than the length of the slot, the ear having converging cam edges defining said mouth, for the purpose set forth. 8. A supporting bracket for a curtain rod, including a forwardly projecting rod supporting ear having opposed vertically spaced keeper notches to receive resilient prongs on an end of the curtain rod, and inwardly converging cam edges defining inwardly tapering entrance clearance from the forward edge of the ear to said notches at points spaced vertically inward from the bottoms of the notches, the maximum distance between the said cam edges exceeding the vertical distance between the bottoms of the notches and the minimum distance between said cam edges being materially less than said vertical distance between the bottoms of the notches, for the purpose set forth.
